TENSION RELEASE MECHANISM

Euclide Tremblay, Lawrence, Mass.

Application November 4, 1931, Serial No. 573,014

2 Claims. (Cl. 139—187)

This invention relates to an accessory or appurtenance for use on conventional looms, and it has more specific reference to a structure which is properly described as a tension release mechanism.

Briefly, the inventive conception comprehends the provision of a novel mechanism especially devised and constructed to release the tension on a shuttle when the picker is ready to throw the shuttle across.

The purpose of the invention is to provide an automatically operable tension release mechanism designed to permit a loom to be run at high speed without burning pickers, saving on the pick motion, such as picker sticks, pickers, pick rolls, and shoes, and otherwise fulfilling the requirements of the mechanism of this class in a highly satisfactory manner.

In the drawings:

20 Figure 1 is a front elevational view of the lay of a conventional loom with the oscillatory tension release mechanism applied thereto.

Figure 2 is an end view of Figure 1 observing the assembly in a direction from right to left.

25 Figure 3 is a vertical sectional view showing the co-operation of the spring-pressed tension producing finger.

Figure 4 is a fragmentary view of the adjustable trip element.

30 Figure 5 is a perspective view of the oscillatory actuator for the rocker arm.

In the drawings, the conventional loom lay is designated by the numeral 6, and the shuttle boxes by the numeral 7. The numerals 8 designate the 35 customary hingedly mounted leaves co-operable with the shuttles 9. The lay sword or leg is indicated by the numeral 10, and the crank arm by the numeral 11 (see Figure 2).

The attachment comprises a pair of brackets 40 12 provided with bearing eyes 13, these being suitably fastened to the lay. These bearings serve to accommodate the oscillatory actuator 14. This actuator is formed from a single rod having a horizontal portion 15 mounted for oscillation in the 45 bearings 13 and constituting a rocker shaft, the intermediate portion of said rod being bent as indicated at 16 to underlie the shuttle box, and the opposite end portion of the rod being fashioned as indicated at 17 to provide an actuating 50 arm.

There is a fixture on the upper end of this arm comprising a sleeve 18 attached by a set screw 19 and said sleeve is provided with a finger 20 cooperable in proper timed relation with the crank 55 arm 11.

In order to maintain the finger 20 in contact with the crank arm 11 and to provide the desired timed tension release action, I provide a coiled spring 18', the same being secured as at 19' to the peculiarly bent portion 16 of the rocker 14. A link 20' serves to anchor the spring to the leg 10 through the medium of an attaching bracket 21.

The oscillatory actuator 14 is provided with desired tension producing means which is here shown in the form of an arm 22 having a collar 23 adjustably secured by set screws 24 on the rocker shaft 15. Thus the arm may be described as a rocker arm, and its free end is bent into V-shaped form as indicated at 25 and the apex portion 26 thereof co-operates with the hinged leaf 8 15 which in turn bears against the adjacent shuttle.

Each leaf or binder 8 has a plate 8' attached thereto which is engaged by the portion 26 of the arm 22, as shown in Figures 1 and 3, and these plates partly bridge the spaces between the leaves or binders 8. As is well known, the shuttle enters the shuttle box on the forward motion of the lay, and the box moves up or down also at this time, so that by having the plates on the binders, the finger 22 rides on these plates while the box is being shifted and thus the pressure of the finger remains on the binder longer, giving the shuttle time to set before the finger leaves the binder. The idea is to have pressure on the binder as long as is possible before the shuttle is ready to be thrown across the loom, at which time all the pressure is taken off.

30 The spring action is applied to the bent portion of the oscillatory actuator so that the finger 20 is maintained in contact with the crank arm 11 and the hooked end of the rocker arm is pressed yieldably against the adjacent leaf or plate 8.

The mechanism is applicable to each end of the 35 loom and provides the desired timed yieldable regulation of the tension to the shuttle but when the crank arm 11 moves upwardly in rocking the lay forwardly the engagement of the arm 20 by the crank arm 11 will move the member 14 to cause a rocking motion of the part 15 in the bearing 13 so that the finger 22 is swung outwardly to release the tension from the leaf 8 so that the picker stick can throw the shuttle from the box. Thus, as before stated, the presence 45 of this attachment on the loom permits the latter to be run at high speed without burning the pickers and producing a noticeable saving in the pick motion.

50 It is thought from the foregoing description 55

that the advantages and novel features of the invention will be readily apparent.

It is to be understood that changes may be made in the construction and in the combination and arrangement of the several parts provided that such changes fall within the scope of the appended claims.

I claim:

1. An attachment for a loom, said loom comprising a crank arm, a lay sword a shuttle binder and a shuttle box, said attachment comprising bracket means attachable to said loom, a rocker shaft mounted for oscillation in said bracket means, means carried by said rocker shaft for cooperation with said crank arm, a rocker arm carried by said rocker shaft and cooperable with said shuttle binder of said shuttle box, spring means cooperable with said rocker shaft and attachable to said lay sword to maintain said arm in yieldable operative position, and a plate at-

tached to said shuttle binder and engaged by a part of said rocker arm and on which said part of said rocker arm rides while said shuttle box is being shifted.

2. An attachment for a loom, said loom comprising a crank arm a lay sword and a shuttle box, said attachment comprising bracket means attachable to said loom, a rod member mounted for oscillation in said bracket means and so formed between its ends as to form a rocker shaft and an upstanding trip member, a bracket on the upper portion of said trip member including a finger cooperable with said crank arm, a spring attached to the intermediate portion of said rod member and having means for anchorage to said lay sword, and a rocker arm secured to said rocker shaft having its upper portion offset and cooperable with said shuttle box.
